Primary Examiner — Catherine A Tuttle(74) *Attorney, Agent, or Firm* — Vorys, Sater, Seymour & Pease LLP; William Klima(57) **CLAIM**

The ornamental design for a bathroom dispenser, as shown and described.

DESCRIPTION

FIG. 1 is a perspective view of showing my new design for a bathroom dispenser

FIG. 2 is a front elevational view thereof;

FIG. 3 is a rear elevational view thereof;

FIG. 4 is a right side elevational view thereof; the left side elevational view being a mirror image of FIG. 4;

FIG. 5 is a top plan view thereof; and,

FIG. 6 is a bottom plan view thereof.

The parts delineated in dashed lines form no part of the claimed design.

1 Claim, 6 Drawing Sheets(56)
